US00D716335S

(12) **United States Design Patent**
Chotin et al.

(10) **Patent No.:** **US D716,335 S**
(b4) **Date of Patent:** **** Oct. 28, 2014**

(54) **DISPLAY SCREEN OR PORTION THEREOF
WITH A GRAPHICAL USER INTERFACE**

(71) Applicants: **Dimitri Chotin**, Vancouver (CA); **Mike Fisher**, Delta (CA); **Mehrdad Fatourechi**, Vancouver (CA); **Shahrzad Rafati**, Vancouver (CA)

(72) Inventors: **Dimitri Chotin**, Vancouver (CA); **Mike Fisher**, Delta (CA); **Mehrdad Fatourechi**, Vancouver (CA); **Shahrzad Rafati**, Vancouver (CA)

(73) Assignee: **BroadbandTV, Corp.**, Vancouver (CA)

(**) Term: **14 Years**

(21) Appl. No.: **29/454,300**

(22) Filed: **May 8, 2013**

(51) LOC (10) Cl. **14-04**

(52) U.S. Cl.

USPC **D14/486**

(58) **Field of Classification Search**

USPC **D14/485-495; D18/26, 31, 32, 33; D20/11, 12, 23, 24, 25, 29, 30, 31, 32, D20/36, 37, 38; 715/702, 764, 838**
